BLADE PACKAGING

Nicholas Testi, Boston, Mass., assignor to Gillette
Safety Razor Company, Boston, Mass., a corpo-
ration of Delaware

Application November 26, 1943, Serial No. 511,785

6 Claims. (Cl. 206—16)

1

This invention relates to the packaging for distribution of fine edged blades, such as safety razor blades and particularly those protected by a cover of sheet material.

In handling safety razor blades under commercial conditions of transportation and distribution and in the more or less casual treatment of such blades by the user, the extremely fine keen edge of the blade is likely to become dulled by being brought into contact with its wrapping or with other objects before it can be actually clamped in shaving position in the razor. On this account the best and most skillful efforts of the manufacturer in sharpening blades are often brought to naught because of the damage done to the very fragile and delicate structure of the blade edge after it has been brought to the keenest possible shaving condition and before the shaving operation is actually undertaken.

An important object of the present invention is to provide an efficient and convenient form of packaging open-end razor blades, that is to say, blades having a longitudinal slot which opens through one unsharpened end edge of the blade. An open-end blade of thin flexible steel has the capacity of springing transversely at its open-end. Its two side portions may be resiliently moved apart against slight resistance but will at once resume normal position when the distorting force is removed. I take advantage of this characteristic in providing the novel package and container of the present invention. The container may comprise an elongated enclosure of any description having top and bottom walls between which extends a blade-locating and retaining device having one section of such dimension that it may be received with clearance in the blade slot and another section of greater width which can be received only in a wider aperture in the blade, such as an enlargement in the blade slot. A blade thus retained in a container or in packaged formation may be individually removed by temporarily springing apart the side portions of the blade. This procedure lends itself well to the packaging of open-end blades which are protected by a cover arranged to be removed only when the blade has been fully located in the safety razor wherein it is to be used.

These and other features of the invention will be best understood and appreciated from the following description of several preferred embodiments thereof selected for purposes of illustration and shown in the accompanying drawing, in which:

2

Fig. 1 is a view in perspective and on an enlarged scale of a package comprising a container and a stack of protected open-end blades enclosed therein;

5 Fig. 2 is a plan view of the same package with portions broken away and showing a blade partially removed from the enclosure;

Fig. 3 is a view in perspective, with portions broken away, illustrating a modified form of container;

10 Fig. 4 is a view in perspective of still another form of container shown with its parts in exploded relation; and

Fig. 5 is a view in perspective of the blade package in book form.

All of the views are drawn on an enlarged scale which is substantially twice actual size.

The invention is herein shown in its application to an open-end blade of a well-known, com-

20 mercial type, that is to say a double-edged blade 10 having both longitudinal edges sharpened for shaving and having in each corner a substantially rectangular recess defining at the ends of the blade elongated unsharpened portions 11

25 and 13. The blade is provided with a central longitudinal slot 12 which opens out with flaring walls through the elongated unsharpened portion 13. The slot 12 is provided at a convenient location in its length with a square or di-

30 amond-shaped enlargement 14 disposed with its edges making an angle of substantially 45° with a longitudinal axis of the blade. The slot 12 is also provided at its center with recesses forming a central circular enlargement 15 for the re-

35 ception of the stem of the cap of the razor. The slot 12 is also provided in its length with a number of smaller enlargements of different sizes and terminates in enlargements giving the end of the slot transverse curvature.

40 Preferably and as herein shown each blade is protected by a cover of sheet material 17. This cover is shaped to be folded over the shoulders adjacent to the end portion 13, extending above and beneath the blade and a slight distance

45 transversely beyond its sharpened cutting edges. At the other end of the blade the cover includes tongues which are folded transversely over the end portion 11 of the blade and these tongues and the wrapper beneath them extend for a

50 substantial distance beyond the end of the blade. A convenient handle is provided in this manner by which the individual blade may be grasped when it is to be removed from its container or package and by which it may be presented to the

55 razor in which it is to be used.

The exact shape of the slot and its enlargements are of secondary importance so long as the slot presents opposed edges which are effective for locating the blade transversely in a razor or in a container and an enlargement of greater width somewhere in its length of a shape suitable to receive a stud or other projection of greater diameter than the normal width of the slot.

In Figs. 1 and 2 is shown an elongated sheet metal container substantially rectangular in outline and having a bottom 20, upright side walls 21 and a top wall 22 made up of two inturned sides meeting throughout a portion of their length in the longitudinal axis of the container. Projecting from the bottom of the container is a straight narrow blade-locating rib 23, and in alignment with the rib and spaced from one end thereof is a cylindrical stud 24 of greater diameter than the thickness of the rib. The two sides of the top 22 of the container are slotted to clear the rib 23 and are correspondingly recessed at their meeting edges to clear the stud 24. The cover 22 is also provided at one end with a rectangular notch exposing the covered end of the blades and providing an opening through which the user may grasp the uppermost blade for the purpose of removing it. The width of the rib 23 is such that it receives the slot 12 of the blade with clearance and the diameter of the stud 24 is such that it will fit freely into the enlargement 14 of the blade slot but will not pass through the slot 12 without spreading the two sides of the blade.

Ordinarily in assembling the blade package of Figs. 1 and 2 a stack of five to ten individual blades is placed in position upon the stud 24 and the rib 23 before the two sides of the cover 22 are folded inwardly. The container is closed and the package completed by folding the sides of the top into a horizontal position parallel to the bottom 20 and, since the stud and rib both pass upwardly above the plane of the top 22, individual blades can be withdrawn only by pulling them forcibly endwise out of the container. In this operation the inclined side edges of the enlargement 14, in cooperation with the stud 24, act to pry apart the two side portions of the blade as suggested in Fig. 2 and in this condition the blades may be one by one forcibly disengaged from the stud 24 and withdrawn from the container. As soon as the stud 24 has passed out of the blade slot 12 the sides of the blade spring back into their normal relationship.

In Fig. 3 is shown an elongated container which may be constructed of either sheet metal or fiberboard or the like. It is similar in shape to the container of Figs. 1 and 2 except that it is not slotted or perforated for a rib or stud. It comprises a bottom 30, upright side walls 31 and a top 32 formed by folding the material of the container inwardly at each side to a meeting line. Instead of a solid rib and stud the container of Fig. 3 is provided with a skeleton rib 33 comprising spaced sheet metal walls and these walls are provided with projecting tongues 34 which may be passed through the top and bottom of the container and clinched. At the left-hand end as shown in Fig. 3 the skeleton rib merges into the form of a split cylinder 35 of greater external diameter than the width of the rib 33. The split cylinder or boss 35 has the function of the stud 24 in retaining the individual blades in stacked relation but in removing a blade the resilient walls of the split cylinder are free to collapse somewhat so that the blade is released by the

combined collapsing action of the cylinder walls and the simultaneous separating movement of the sides of the blade. The top of the container is cut away at one end in a large rectangular notch so that the wrapped ends of the blade are exposed beneath it and may be readily reached by the user.

In assembling the blade packages of Figs. 1-3 a stack of assembled blades may be dropped over the stud 24 and the rib 23, or rib 33 and its split cylinder 35, before the container is closed, the step of closing the container bringing the two sides of its top into their final position. When this has been done the blades may be removed only individually by endwise movement with sufficient force to spread the open end of the blade or collapse the split cylinder in the package of Fig. 3.

In Fig. 4 my invention is shown as embodied in a tuck of the general type now used in dispensing four to ten blades. This package comprises a rectangular cardboard enclosure 40 having end flaps 41 and 42 and an end portion 43 in its body which is set off from the rest of the enclosure by a transverse slit and inclined row of perforations in each side wall so that the whole end of the enclosure may be broken off easily by the thumb of the user. A thin rectangular base plate 44 is arranged to fit within the enclosure 40 and is provided near one end with a stud 45 which in diameter corresponds to the thickness of the rib 23 and is freely received within the slot 12 of the blade, and a stud 46 of larger diameter which corresponds to the stud 24 having a greater diameter than the slot 12 of the blade of such shape as to fit freely within the square-sided enlargement 14 of the blade slot. A stack of covered blades is shown as positioned by the studs 45 and 46 upon the base plate 44 and this assembled stack is arranged to be pushed into the enclosure as a unit. The ends of the studs 45 and 46 then pass into spaced perforations provided for that purpose in the top of the enclosure. In this manner the loaded unit is retained within the enclosure where it may be sealed by folding inwardly the end flaps 41 and 42. When the end portion 43 of the enclosure is broken away the user is free to grasp the projecting ends of the folded cover 17 and forcibly remove one after another from the stack.

In Fig. 5 is shown an elongated pasteboard container of the book type comprising upper and lower covers 50 connected by a vertex section 51 set off by transverse perforated lines. A tubular stud 52 of small diameter and a similar stud 53 of relatively large diameter extend between the two cover portions and are riveted in place. The stud 52 in diameter equals substantially the width of the longitudinal slot of the package and the larger stud 53 fits into the square-sided enlargement 14 of the covered blades contained therein in stacked formation. When it is desired to remove a blade from this form of package the vertex section 51 may be bodily torn away thus exposing the folded end of the protective cover 17 of each blade whereby the blade may be grasped and drawn forcibly out of its package.

Having thus disclosed my invention and described in detail several embodiments thereof for purposes of illustration I claim as new and desire to secure by Letters Patent:

1. A container for thin resilient razor blades of the type having a longitudinal slot opening through one end and an enlargement in the slot near its open end, said container comprising an

elongated enclosure having top and bottom walls for covering a stack of blades, and having within it means fitting the blade slot for locating the stack transversely, and a projection extending into both the top and bottom walls of the enclosure and receiving the enlargement of the blade slot and being of greater width than the said slot-fitting means, said projection normally holding the blades against endwise movement and acting to spring the sides of a blade and widen its slot when the blade is forcibly removed, one wall of the enclosure being recessed to permit the user to grasp a blade for the purpose of removing it.

2. A package of open-end razor blades comprising an elongated enclosure having top and bottom walls, a narrow blade-locating rib and a stud thicker than the rib entering both the top and bottom walls of the enclosure, and a stack of resilient blades, each having a longitudinal slot clearing said rib and including near one end an enlargement in which said stud is received and whereby the blade is normally held against lengthwise movement, said stud acting to spring the blade and increase the width of its slot temporarily when the blade is forcibly removed, the top wall of the enclosure being recessed to permit the user to grasp a blade for the purpose of removing it.

3. A package of open-end razor blades comprising an elongated enclosure having top and bottom walls and blade-locating means therein which includes a stud projecting into both the top and bottom walls of the enclosure and a stack of longitudinally slotted resilient blades, each with an enlargement near one end of its slot of dimensions to engage said stud, thereby retaining the blade yieldingly against longitudinal displacement and acting to spring the blade and widen its slot when the blade is forcibly removed, the top wall of the enclosure being recessed to afford access to the user for grasping and removing a blade.

4. A package of flexible open-end razor blades comprising an elongated enclosure having at least upper and lower walls spaced from each other, a narrow blade-locating projection located centrally in the enclosure between said upper and lower walls and a wide blade-locating projection extending at both ends into the planes of the upper and lower walls of the enclosure, in combination with a stack of open-end blades, each having a central longitudinal slot widening into an intermediate enlargement and receiving the

wide projection therein while the narrow projection is received by said slot, the individual blades of the stack being yieldingly movable in an endwise direction for removal from the enclosure and the wide projection acting to spring the blade and temporarily open its slot when the blade is forcibly removed, the top wall of the enclosure having been recessed, thereby providing an opening through which the user may grasp a

10 blade for the purpose of removing it.

5. A package of flexible razor blades comprising an elongated enclosure having top and bottom walls and containing a detent extending at both ends into the planes of said walls, in combination

15 with a stack of protected blades, each having an open-end aperture shaped to spring around said detent and being individually and yieldingly retained in place in the package by engagement with the detent, the top wall of the enclosure being recessed to provide an opening through which the user may grasp a blade for the purpose of removing it.

6. A package of flexible razor blades comprising an elongated enclosure having top and bottom walls and a stud therein extending at both ends

20 into the respective planes of said walls, in combination with a plurality of blades, each having a longitudinal open-end slot narrower than the stud and having an enlargement wide enough to

25 accommodate the stud, the enlargement having stud-engaging walls inclined with respect to the longitudinal axis of the blade and acting to pry apart the side portions of the blade when the latter is moved forcibly in an endwise direction, the top wall of the enclosure being shaped to

30 afford the user access to the uppermost blade for the purpose of removing it.
